AUXILIARY CHARGE REGULATING DEVICE

Jay A. Bolt, Ann Arbor, Mich., and Robert W. Moore, South Bend, Ind., assignors to Bendix Aviation Corporation, South Bend, Ind., a corporation of Delaware

Application May 22, 1947, Serial No. 749,716

7 Claims. (Cl. 123—119)

1

This invention relates to an auxiliary charging device for internal combustion engines and other power units to which it may be adapted; it is particularly concerned with so-called water injection systems or devices by means of which an auxiliary charging component (which may be water, alcohol, water-alcohol mixtures, liquid saturated hydrocarbons and other solutions, or a mixture thereof) is incorporated in the normal fuel-air mixture during the charging operation to modify the action of the charge, as by functioning as a coolant or antidental, antitoxic agent or otherwise. For the sake of brevity, however, the auxiliary charging fluid is in some instances referred to simply as "water" in the following description.

The present application constitutes an improvement on, or an alternate type of auxiliary charging device relatively to, that disclosed in the copending application of Frank C. Mock, Serial No. 588,023 filed April 12, 1945; it also embodies a fuel-metering and derichment system of the type described and claimed in another copending application of the said Frank C. Mock, Serial No. 745,003 filed April 30, 1947.

The auxiliary charge metering device of application Serial No. 588,023 incorporates a poppet valve which flows water at a substantially constant head to a metering valve arranged to automatically vary the area of a metering orifice as a function of an engine condition or conditions, for example, charge pressure and temperature, and it also incorporates a derichment valve control valve which, should the water supply pressure drop below a predetermined value, will close and open the derichment valve. However, there may be conditions arise under which the derichment control valve of the device of Serial No. 588,023 will not close promptly, and an object of the present invention is to avoid such contingency.

Another object is to provide an auxiliary charging device which may be depended upon to meter an auxiliary charging fluid in a predetermined ratio to a primary fuel and which will cut in and out automatically under predetermined charge conditions.

Another object is to generally improve devices of the type specified.

The foregoing and other objects and advantages will become apparent in view of the following description taken in conjunction with the drawings, wherein:

Figure 1 is a schematic view, principally in elevation, of a carburetor of the speed metering type

2

having the water metering device of the present invention operatively associated therewith;

Figure 2 is a sectional view of the bottom portion of Figure 1, showing the primary fuel metering valve and derichment valve, and coacting parts; and

Figure 3 is an enlarged sectional view of the water metering unit.

Referring to the drawings and first to Figure 1, 10 a primary fuel may be metered to an engine 120 by a carburetor of the speed type generally indicated at 10. Since the particular structure of the carburetor 10 has no bearing on the invention, only such parts are shown in detail as directly 15 coact with the auxiliary charge or water metering device. Briefly, it includes a pressure feed pump which receives fuel by way of a conduit 12 and is driven in synchronism with the engine by means of a suitable drive connection such as the 20 gear 20, the pump driving a centrifugal governor and at the same time supplying fuel under pressure to a chamber in which the governor is mounted. The governor is operatively connected to a poppet valve disposed in the fuel conduit upstream of a main metering orifice 60 and a supplemental metering orifice 61, and controlling 25 flow of fuel to said orifices, the said valve having connected thereto a metering head diaphragm which opposes the opening force exerted on the 30 valve by the governor; the arrangement being such that the poppet valve regulates the metering head to be proportional to engine speed for a given area of said orifices. The areas of the 35 metering orifices 60 and 61 are variable, however, by means of a single metering needle 96 which is provided with a pair of contoured metering sections 97 and 98. The position of the needle 96 is varied in relation to changes in manifold pressure modified by exhaust back pressure and 40 accordingly it is slidable in a bushing 89 and is connected to the movable end of a manifold pressure bellows 100 mounted in a housing 101 to which manifold pressure is communicated by way 45 of a conduit 102, see also Figure 1. The manifold pressure bellows 101 is in turn connected to the movable end of a smaller bellows 103, responsive to changes in atmospheric pressure and hence exhaust back pressure and which is anchored to the adjacent end of the housing 101 and has its interior vented at 104 to the atmosphere. For an understanding of the construction and operation of the bellows assembly 100, 103, reference may be had to a copending application of Frank C. Mock, Serial No. 586,223. Briefly however, in operation, the manifold pres-

Sure bellows 100 responds to changes in manifold pressure while the bellows 103, being vented to atmosphere, responds to changes in atmospheric pressure which is an index of exhaust back pressure. As manifold pressure increases, the bellows or capsule 100 is compressed, thereby retracting needle 60 from the metering orifices 60, 61, and as manifold pressure decreases, the bellows 100 expands and projects the needle 60 into said orifices, this action being modified by travel of the bellows 103 in relation to changes in atmospheric pressure, while temperature responsive needle 80 controls metering of fuel across the bypass 63, port 91 and passages 92, 92'.

The main metering orifice 60 constitutes a variable restriction between an unmetered fuel chamber C and a metered fuel chamber B, the latter being in communication with the metered fuel line 55. A supplemental or enrichment metering orifice is indicated at 61; it is in alignment with the orifice 60 and constitutes a like restriction for regulating the flow of fuel from chamber C by way of passages 63, 63' and valve port 64 to chamber 65 and thence through the said orifice 61 to chamber B. Valve port 64 is controlled by a selectively operable derichment and mixture selector valve 66 which is slidable in a bushing 67 and at its lower end is connected to a diaphragm 68. A spring 69 normally urges the valve 66 toward open position. Another diaphragm 70 is arranged in spaced relation with respect to the diaphragm 68 and in conjunction with the latter defines a chamber 71. A one-way abutting connection is provided between the lower diaphragm 70 and the upper diaphragm 68 by a member 72 which is secured to the bottom or adjacent end of the valve 66 and constitutes a reinforcement for the upper diaphragm. When the lower diaphragm moves upwardly, the central reinforcing plate 73 thereof engages the member 72.

Beneath the lower diaphragm is a pressure chamber 74 to which an operating pressure may be applied to close the valve 66 when an antide-ontant is to be metered to the engine, as will be more fully hereinafter described.

For the purpose of selecting an auto-lean or auto-rich fuel-air ratio, fuel under pressure from the carburetor may be conducted by way of conduit 86' to a chamber 71 between the upper and lower diaphragms 68 and 70 by means of a mixture selector unit or valve assembly which forms no part of the present invention, its specific structure and method of operation being disclosed in the copending application of Frank C. Mock, Serial No. 745,003, hereinbefore identified. That part of the control system shown in Figure 1 includes an electric solenoid valve 75 provided with an electrical connector or plug 82, a circuit wire 82' connecting the live terminal of the plug with the one contact 229 of a manifold pressure switch 230, to be described, the opposite contact 229' of the switch 230 connecting by wire 82'' with a contact 83' adapted to be selectively engaged by a manually operable switch 83 located in the pilot's compartment or within easy access of an operator and connected in circuit with a battery 84' by wire 84.

The metered fuel in chamber B flows by way of fuel line 55 into a chamber 106 (note Figure 3) and thence into discharge nozzle chamber 107, from which it is discharged through a nozzle opening 108 into intake conduit 109 posterior to throttles 110, 110'. The discharge opening 108 is controlled by a discharge nozzle 111, which may

be of any preferred pressure type; as shown in the present instance, it is slidable in a bushing 112 and has its stem connected to a diaphragm 113 backed up by a spring 114 mounted in a housing or cover 115, the interior of the latter being vented to the air intake conduit upstream of the throttles 110 by means of passages 116 and 117. When the fuel pressure in chamber 106 attains a predetermined value, for example, ten p. s. i., the nozzle is retracted from the opening 108 and fuel is discharged into the air intake conduit 109. The chamber 106 contains metered fuel only during normal periods of operation, or without water injection, but when water is being injected, this chamber together with the nozzle chamber 107 also serves as a mixing chamber.

The engine diagrammatically illustrated at 120, Figure 1, is of the radial type and provided with a plurality of cylinders 121 to which air under supercharger pressure is directed by way of manifold 122 and manifold pipes 123, an engine driven or first stage supercharger being indicated at 124. While not shown in the schematic view of Figure 1, the system is adapted for use with a second or auxiliary stage supercharger located anterior to the throttles 110, 110'. The intake conduit 109 is shown connected to a throttle body 145 through which the passage 117 extends and opens out into the main air intake passage upstream of the throttles 110. A temperature responsive element 94 is adapted for mounting in the intake manifold and acts by way of a fluid conduit 95 and bellows 93 to regulate the temperature needle 90, Figure 3.

The device generally indicated at 125 is an accelerator pump; it is actuated from the throttles 110, 110' by means of a link 136 and arm or lever 135'. The throttles 110, 110' are mounted on a pair of shafts 138 and 141, which are interconnected for synchronous movement by bell crank lever 137, link 139 and arm 140, the bell crank 137 being also connected to the link 136.

The antide-ontant or water metering unit is generally indicated at 150; it is shown in elevation in Figure 1 and in schematic or sectional diagram in Figure 3. Referring to the sectional view, a main casting or housing 151 is anchored to a boss 152 formed on the section 109 of the intake conduit adjacent the throttle body 145. The casting 151 is formed with a water inlet chamber 153, an unmetered water chamber 154, a metered water chamber 155, and a discharge chamber 156. Water is taken from a suitable supply such as a water tank, not shown, and flows by way of a conduit 157, Figure 1, to and through a strainer 158 into the chamber 153. A pump 159 is mounted in conduit 157; it may be of conventional construction having an inbuilt by-pass rendered operative when a predetermined delivery pressure is encountered, and it may be operatively connected to a power control device as illustrated and described in the copending application of Stanley B. Smith and Frank C. Mock, Serial No. 533,296, filed April 29, 1944, and which latter application also embodies certain features in common with the water metering device as herein disclosed. The water pump is shown in Figure 1 as being electrically driven from a suitable source of supply such as the battery 84', which connects with the pump motor by way of wire 160, switch 161, contact 160' and wires 162, 162', the switch 161 being under manual or automatic control, as desired.

Controlling flow of fluid between chambers 153 and 154 is a pressure regulating valve 163, Figure

3, herein termed the poppet valve since it is of the poppet type, said valve being slidable in a valve housing or guide bushing 164 formed with a port or ports 165 and a valve seat 166. A spring 167 normally urges the valve 163 toward seated position, said spring being adjustable by means such as shims 168. The body of the valve 163 is hollow and at its upper end the valve wall is formed with a bleed 169, the latter permitting a restricted by-pass flow of water from chamber 153, thence through the hollow valve body and a passage 169' to chamber 154, so that when the valve is closed, the pressures in said chambers will become equalized under certain conditions and for a purpose to be described.

Overlying chamber 154 is a diaphragm 170; it has its peripheral edge clamped between a cap or cover 171 and the adjacent surface of the main casting 151, and its central portion is engaged between a pair of clamp members on a guide rod 172 whose upper end projects into a guide pocket or recess formed by the cap 171 and whose lower end carries a ball head 172' in contact with the stem of valve 163. A spring 172 encircles the guide rod 172 and normally urges the latter in a valve opening direction, or downwardly, as shown in Figure 3. The cap 171 defines a chamber 174 above the diaphragm 170 which is vented to metered water pressure by a passage 175.

A metering valve is indicated at 176; it controls the area of a metering orifice 177 through which water flows from chamber 154 to chamber 155. The valve 176 has a stem which projects through a guide member forming part of a bushing 178 which closes off chamber 155 from a bellows chamber 179 in which is mounted a pressure responsive spring loaded bellows 180. One end of the bellows 180 is anchored by means of a threaded stem 181 to a cap or cover 182, while the opposite or movable end thereof is provided with a cup-shaped member having an abutting connection with the stem of the valve 176, a light spring 183 encircling the valve stem and normally urging the said stem against said member. A passage 184 communicates interstage duct pressure to the bellows chamber 179, which pressure for engines having certain characteristics has proven satisfactory as a reference pressure for the water metering valve 176. However, this reference pressure may be taken from the intake manifold direct or from any other suitable point, as desired and found advisable for the particular engine to which the water metering system may be applied.

A check valve 185 prevents backflow of fuel into the water metering system from chamber 156; the pressure at which it will open being predetermined by adjustable spring 186.

A derichment valve control valve is indicated at 190; it controls a port 191 through which inlet water pressure may be communicated by way of passage 192, chamber 193 and conduit 194 to the chamber 74 of the valve 66 (compare Figure 3 with Figures 1 and 2). The valve 190 is connected to a diaphragm 195 which forms a movable wall between the chamber 193 and a chamber 196, the latter being in communication with the unmetered water chamber 154 by way of passage 197. A spring 198 is located in the chamber 196 and normally urges the valve 191 toward seated position; it predetermines the differential pressure acting on the diaphragm 195, at which the valve 191 will open, and it closes the valve when the differential drops below a certain value. A vent passage 199 communicates chamber 154 as well as chamber 196 with a line 200 leading back

to the water tank, not shown, to insure closing of the derichment control valve under certain conditions and to also vent the system of air before the water reaches the metering valve. A restriction or bleed 201 communicates conduit 194 with the line 200 to insure proper functioning of the valve 66.

It is generally desirable to have an arrangement whereby the manifold pressure will be automatically increased when water is injected, and automatically returned to normal should the system fail or run dry, or when the water supply pressure drops below a predetermined value. The particular or specific means by which this may be accomplished forms no part of the present invention. For example, a pressure switch, Figure 1, may be used, said switch comprising a cylinder 205 having mounted therein a piston 206 which carries a bar 207 of conducting material provided with contacts 208 and 209 adapted to engage companion contacts 210 and 211 carried by an insulated bar 212, the latter being inserted in an electric circuit including ground wires 213, 214 for the coil 215 of a solenoid valve 216, the coil 216 being placed in circuit with the contact 160' by means of wires 217 and 162.

A manifold pressure bellows 218 is mounted in a chamber 219 and forms part of a boost control which operates in general like that illustrated in the Smith and Mock application Serial No. 533,296, heretofore noted. The manifold pressure bellows constitutes part of a variable datum assembly including a datum rod 220 which is connected to the movable end of the bellows 218 and is encircled by datum spring 221, adjustable by means of a lever 222 engaging a slidable bushing or collar 223. The lever 222 is adapted to be controlled from a pilot's power control member or quadrant, not shown. The arm or lever indicated at 224 may control a servo valve for a servo system and coacting mechanism which operates to maintain power for a given datum setting by opening the throttles until engine stage supercharger capacity is attained and thereafter increasing the drive on the auxiliary stage system, not shown; it is movable both in response to manual adjustment of the datum spring 221 and in response to movement of the bellows 218 due to changes in manifold pressure. Thus, assuming the power control lever has been set for a given manifold pressure, should the pressure in the chamber 219 drop, due, for example, to a gain in altitude, the bellows 218 will extend itself and thereby open the throttles 110, 110', and/or regulate the drive on the supercharging system to maintain such manifold pressure.

The manifold pressure chamber 219 is in communication with the intake manifold of the engine by way of conduit 225 and a branch conduit 225' having a bleed 226 therein, and said chamber may also be placed in communication with a lower pressure source, such as the intake conduit 108, by way of a conduit 227 having a bleed 228 therein, the solenoid valve 216 controlling said latter conduit. When the solenoid valve 216 is open, the pressure in chamber 219 is lowered independently of the action of the lever 222, and hence the manifold pressure will be increased due to extension of the bellows 218, the manifold pressure resuming its normal value upon closing of the solenoid valve 216.

The manifold pressure switch 230 is controlled by a bellows 231 mounted in a housing 232, the latter defining a bellows chamber 233 which is in pressure communication with the engine in-

take manifold by means of conduits 234 and 225. A spring 235 mounted in the bellows 231, normally urges the switch 230 to closed position. This manifold pressure switch is primarily a safety switch in that it insures against the use of an auto-lean fuel-air ratio when the manifold pressure is above a given value.

The antidental or water metering unit operates as follows:

In the position of the parts as shown in the drawings, the switch 83 has been turned to normal or auto-rich position and the water pressure switch 161 to "on" position; the electric solenoid valve 75 is de-energized, relieving pressure from the chamber 71 between the upper and lower diaphragms 68 and 70, while the derichment valve control valve 190 is open and water pressure has been communicated to the pressure switch 205, thereby raising the manifold pressure, and also to chamber 74 beneath the lower diaphragm 70, thereby closing the derichment valve 66. Metering of primary fuel now takes place through the main metering orifice 60 only.

The conduit 157 and chambers 153, 154, 155 and 156 may be considered a continuous flow passage terminating in the mixture chamber 106. Assuming the pilot of an airplane equipped with a system such as that herein disclosed desires to go into emergency power with accompanying water injection and has turned switch 161 to contact 160', as in Figure 1, the water pump starts operating and builds up pressure in the chamber 153 and water flows across the poppet valve 163 (which is then open due to spring pressure) and into the chamber 154, where it acts on the diaphragm 170 in a direction tending to close the poppet valve. From chamber 154, the water flows through metering orifice 177 into chamber 155, and from the latter chamber pressure is communicated to chamber 174 on the opposite side of the diaphragm 170. Since metered water pressure is substantially equal to discharge nozzle pressure (neglecting the drop across the check valve 185) the valve 163 will maintain the pressure in chamber 154 at a substantially constant value above discharge nozzle pressure as determined by the force of spring 173, and this will produce a substantially constant drop across the metering valve 176 so that the metering of water will be in proportion to the effective area of the metering orifice 177. The position of the valve 176 which controls this orifice is governed by the bellows 180, which is vented to interstage duct pressure. For an engine of the type shown, interstage duct pressure constitutes a fairly accurate reference pressure for the desired water-to-fuel ratio.

The diaphragm 195 of the derichment control valve 190 is responsive to the drop or differential across the poppet valve 163, which differential tends to open the derichment control valve against the resistance of the spring 198. If adequate water supply pressure exists but for some reason no water is flowing across the metering valve to the discharge nozzle, or should the poppet valve become stuck, there will be no poppet valve drop (this being assured even though the poppet valve 163 should be tightly closed by the small bleed 169 in parallel with the poppet valve 163, which will then equalize the pressures in chambers 153 and 154), and since there will then be no differential pressure across the diaphragm 195, the spring 198 will close the valve 190. In case the supply of water should become exhausted and the supply pressure drop, there will be a

diminishing force acting on the derichment control valve diaphragm in a valve opening direction, whereupon the spring 198 will close the valve 190 when the supply pressure drops to a predetermined value. For example, should the water system run dry with the pump 159 still running, the latter might otherwise build up sufficient air pressure in the device to maintain the derichment control valve 190 open, a hazard which is overcome by the method of derichment valve control herein disclosed.

When the derichment control valve 190 opens, water pressure is communicated to the pressure switch 205, the solenoid valve 216 is opened, thereby bleeding pressure from bellows chamber 218 and the manifold pressure is increased; and water pressure is also applied by way of conduit 194 to the chamber 74 of the derichment valve 66, and both of the diaphragms 68 and 70 move upwardly and close the derichment valve 66. Whenever the water supply runs out, or should the switch 161 be opened and the water pump stopped, valve 190 will close and pressure will be relieved from the chamber 74 by way of conduit 194 and vent conduit 200, while at the same time pressure will be relieved in back of the pressure switch piston 206, the circuit to the solenoid valve 216 broken and the latter will close, thereby returning the manifold pressure to its previous value. The carburetor will then meter on a normal or auto-rich fuel-air ratio.

It will be apparent that certain modifications and rearrangements of parts will be obvious to those skilled in the art, and the invention is therefore not limited to the specific structure used for the purpose of illustration, but only by the appended claims.

We claim:

1. In a fuel feeding system for an engine, in combination, a device for supplying a primary fuel to the engine, a derichment valve operatively associated with said device for obtaining a predetermined fuel-air ratio when an antidentalant is to be injected with the primary fuel, an auxiliary charge injection system for metering the antidentalant, said auxiliary charging system including a flow passage having a metering orifice therein, a regulating valve upstream of said orifice for maintaining a metering head across said orifice, a derichment valve control valve, and means for rendering said latter valve responsive to the drop across said regulating valve.

2. In a fuel feeding system for an engine, in combination, a device for supplying a primary fuel to the engine, a derichment valve operatively associated with said device for obtaining a predetermined fuel-air ratio when an antidentalant is to be injected with the primary fuel, an auxiliary charging system including a flow passage having a metering orifice therein, a regulating valve upstream of said orifice for maintaining a metering head across said orifice, a derichment valve control valve, means for rendering said latter valve responsive to the drop across said regulating valve, said means including a diaphragm connected to the said control valve and subjected to the differential in pressures upstream and downstream of said regulating valve, and a spring adapted to seat said control valve when the differential pressure drops to a predetermined value.

3. In a fuel feeding system for an engine, in combination, a device such as a carburetor for supplying a primary fuel to an engine, a derichment valve operatively associated with said de-

vice for obtaining a predetermined fuel-air ratio when an antidetonant is to be injected with the primary fuel, an auxiliary charge injection system for metering the antidetonant including a flow passage for the antidetonant having a metering orifice therein, a regulating valve upstream of said orifice for maintaining a predetermined metering head across the orifice, a derichment valve control valve, a diaphragm mounting said control valve, a spring normally urging said control valve towards seated position, means subjecting said diaphragm to the drop across the regulating valve, the arrangement being such that when the differential across said diaphragm is at a predetermined value, said spring closes said control valve to thereby close the derichment valve.

4. In a fuel feeding system for an engine, in combination, a carburetor for supplying a primary fuel to the engine, a derichment valve operatively associated with said carburetor for obtaining a predetermined fuel-air ratio when an antidetonant is to be injected with the primary fuel, an auxiliary charge metering system including a flow passage for antidetonant having a metering orifice therein, a regulating valve upstream of said metering orifice, a diaphragm connected to said regulating valve, means for subjecting said diaphragm to the differential in pressure between metered and unmetered antidetonant, means for regulating the area of said metering orifice as a function of an engine condition, a derichment valve control valve provided with a diaphragm and a spring normally urging the control valve to seated position, means subjecting said control valve diaphragm to the drop across said regulating valve whereby said spring will close the control valve when the drop is at a given value, and a bleed by-passing said regulating valve to insure reduction of the drop across said latter valve in the event the regulating valve is closed and there is supply pressure upstream of the regulating valve but no substantial amount of antidetonant is being passed by the auxiliary system.

5. In a fuel metering system for an engine, in combination, a device such as a carburetor for metering a primary fuel to the engine, a derichment valve associated with said device for obtaining a given fuel-air ratio when an antidetonant is to be metered along with the primary fuel, an auxiliary charge metering device provided with a flow passage for antidetonant having a metering orifice therein, a regulating valve upstream of said orifice arranged to maintain a substantially constant metering head across said orifice, a metering valve for varying the area of said orifice, means responsive to an engine condition controlling said metering valve, means such as a supply pump for delivering antidetonant under pressure to said regulating valve, a derichment valve control valve provided with a diaphragm subjected to the drop across said regulating valve, a spring normally urging said control valve to seated position, the arrangement being such that when the drop across the regulating valve is at a given value the spring will close the control valve, and a bleed or restricted flow passage by-passing the regulating valve to insure reduction of the drop across the regulating valve in the event the latter should be closed while the pump is running and maintaining

pressure upstream of the regulating valve but no substantial amount of antidetonant is being passed by the auxiliary system.

6. In a fuel metering system for an engine having an intake manifold, in combination, a carburetor for metering a primary fuel to the engine, a fuel spray nozzle for injecting metered fuel when the pressure of the fuel attains a predetermined value, an auxiliary charge metering device for supplying an antidetonant to the nozzle with the primary fuel, said auxiliary charge metering device being provided with a flow passage terminating at said nozzle and having a metering orifice therein, a regulating valve upstream of said orifice, a spring normally urging said regulating valve toward open position, a diaphragm connected to the regulating valve and subjected to the differential between unmetered and metered antidetonant and whereby the head across said metering orifice is maintained at a substantially constant value above nozzle discharge pressure as determined by said spring, a metering valve arranged to vary the area of the metering orifice, a bellows connected to said metering valve for positioning the latter, and means rendering said bellows responsive to changes in pressure varying with changes in manifold pressure.
7. In a fuel metering system for an engine, in combination, a carburetor for metering a primary fuel to the engine, a fuel spray nozzle for injecting metered fuel when the pressure of the fuel attains a predetermined value, an auxiliary charge metering device for supplying an antidetonant to the nozzle with the primary fuel, a mixing chamber upstream of the nozzle, said auxiliary charge metering device having a flow passage terminating in said mixing chamber and provided with a metering orifice, a regulating valve upstream of said orifice, a spring normally urging said regulating valve toward open position, a diaphragm connected to the regulating valve and subjected to the differential between unmetered antidetonant and whereby the head across said metering orifice is maintained at a substantially constant value above nozzle discharge pressure as determined by said spring, a derichment valve control valve provided with a spring normally urging it to seated position and a diaphragm subjected to the drop across said regulating valve so that the control valve will open at a given value of the drop, a metering valve for varying the area of said metering orifice, means for automatically positioning said metering valve as a function of an engine condition, and a check valve downstream of said metering valve to prevent backflow from said mixing chamber when the metering pressure of the antidetonant is below the nozzle delivery pressure.
